UNITED STATES PATENT OFFICE.

MASCHIL D. CONVERSE, OF NEW YORK, N. Y., ASSIGNOR TO JOHN J. TOWER,
OF MONTCLAIR, NEW JERSEY.

SAW-CLAMP.

SPECIFICATION forming part of Letters Patent No. 716,385, dated December 23, 1902.

Application filed October 28, 1901. Serial No. 80,319. (No model.)

To all whom it may concern:

Be it known that I, MASCHIL D. CONVERSE, a citizen of the United States, residing at New York, borough of Manhattan, in the county 5 of New York and State of New York, have invented certain new and useful Improvements in Saw-Clamps, of which the following is a specification.

My invention relates to improvements in 10 saw-clamps in which the clamping-jaws are open to receive the saw from below; and the objects of my improvements are, first, to provide means for preventing the saw from chattering; second, to afford instant adjustment 15 and clamping and releasing of the saw, and, third, to reduce the cost of manufacture of such articles. I attain these objects by means of certain mechanisms and their combination and arrangement hereinafter illustrated 20 and described.

Figure 1 is a plan view of my invention, showing its construction and operation in part, a saw *s* being shown in place; Fig. 1½, a detail edge view of a certain part of Fig. 1, 25 and Fig. 2 is a front elevation of the same. Fig. 3 is a detail plan view of parts thereof; and Fig. 4 is a sectional view on line 4-4 of Fig. 1, further showing construction and operation.

30 Like letters indicate corresponding parts throughout the several figures.

A is the main frame, connecting two similar dogs *B B*, which latter each have a raised anvil-head *b b* on the upper side opposite the 35 points to receive the blows of a hammer when driving into a bench, as seen in Fig. 4. At either end there is an arch *C C*, to which is joined the clamp-jaw *D* at its ends. The frame *A* is provided with a bracket *E*, having a hole for a screw at *c* at its lowermost edge. These parts are preferably made integral. *G* is the other and slideable clamp-jaw, which has a flange *g* extending from its 40 middle rearwardly and flush with its under side and through which there is a slot *g* to stride with a free fit a pivotal rivet *h*, which latter is fixed in the frame *A* midway or equidistant from the dogs *B B* and carries pivotally the clamping-lever *L*, the head *i* of which 45 latter is eccentric to the pivotal hole therein and acts against a block-surface *j* of the jaw

50 G. This eccentric head *i* is recessed at one side (shown by the dotted line *k* in Fig. 1) to form a shoulder at *l*, (see Fig. 1½,) whereby (when the lever is moved to the left) through 55 contact with a projection *m* on the surface of the flange *g* the clamp-jaw *G* is drawn away from the jaw *D*.

It will be seen that movement of the lever *L* to the right will cause the eccentric head *i* 60 to engage the surface *j* and push the jaw *G* toward the jaw *D*, the former sliding upon the surface of the frame *A*, and thus instantly grip the saw *s*.

It will be seen that the lever *L* operates in 65 a horizontal plane, consequently is out of the way when the saw-teeth are being filed.

A feature of my invention is comprised in 70 making the jaws *D* and *G* of sufficiently resilient material and so arranging them as to allow of their being sprung out of straight line and recover their normal position by movement of the clamping-lever *L*, which is pivoted intermediate of the ends of the frame, and to this end in so proportioning the eccentric head *i* that the said jaws shall be 75 sprung from the straight line shown by the full lines to the curved position shown by the dotted lines in Fig. 1, the object being to hold the saw *s* on a curve, so as to prevent its 80 chattering and ringing.

It is sometimes desirable to make saw-clamps of the type described of cast-iron or other similar brittle material, and in such case it has been found if the upper surfaces 85 of the arms to which the dogs *B B* are attached are made flat that on driving the points into the wood the arms of the dogs receiving the impact often break. I therefore obviate this difficulty by constructing or casting 90 with raised heads or anvils *b b* immediately opposite the points of the dogs to centralize the blows from the hammer and prevent the latter contacting with the arms.

Having described my invention, what I 95 claim as new, and desire to secure by Letters Patent, is—

1. In a saw-clamp, a frame provided with dogs, and a resilient jaw thereto attached by arches at the ends, and a second resilient 100 slideable jaw, in combination with a horizontally-movable clamping-lever and eccentric-

ally-pivoted head in central engagement with the latter jaw.

2. In a saw-clamp, a frame provided with dogs and a resilient jaw thereto attached by arches at the ends, and a second resilient slidable jaw, and a horizontally movable clamping-lever, in central engagement with the slidable jaw, provided with a shoulder *l* to engage a projection *m* on the slidable jaw.
- 10 3. In a saw-clamp, in combination, a frame provided with anvil-headed dogs and a re-

silient jaw thereto attached by arches at the ends, and a second resilient movable jaw, and a pivoted clamping-lever, in central engagement with the movable jaw.

In testimony whereof I have signed my name to this specification in the presence of two subscribing witnesses.

MASCHIL D. CONVERSE.
